UNITED STATES PATENT OFFICE

2,550,163

RIGID HANDLE AXLE JACK

John H. Phenning, Winona, Minn., assignor to
 Vulcan Manufacturing Co. Inc., Winona, Minn.,
 a corporation of Minnesota

Application February 27, 1946, Serial No. 650,483

12 Claims. (Cl. 254—93)

1

This invention relates to axle jacks, and more particularly to the type which can be easily placed in position by means of the jack handle.

As is well known, the ends of an automobile extend well beyond the axles, and in order to place a jack in position under either axle, it is necessary to reach a considerable distance under the automobile. To thus reach that distance is inconvenient, if not difficult. Jacks of existing types are not susceptible of being easily moved bodily in all directions by means of the handle alone, for placing them in position.

It is therefore an object of the present invention to provide a simple jack with a handle that is inherently rigid and is also rigidly secured to the jack by which the jack can be easily positioned bodily from beyond the end of the automobile.

Another object is the provision of a hand grip at the outer end of the handle to facilitate handling of the jack.

Still another object is the provision of a simple means cooperating with the hand grip for operating the jack.

A further object of the invention is to provide a detachable rigid handle for reduction of space when the jack is not in use and at which time it is desirable to store it in a tool box or under the seat of an automobile, simple means for cooperation between the operating parts on the handle and in the jack proper being provided.

A still further object is the provision of lock means for locking the operating means on the handle for convenience when the jack is not in use.

With these and other objects in view my invention consists in the construction, arrangement and combination of the various parts of my device whereby the objects contemplated are attained, as hereinafter more fully set forth, pointed out in the claims, and illustrated in the accompanying drawings, in which:

Fig. 1 is a view, partly in vertical section and partly in elevation, of the jack and handle.

Fig. 2 is a fragmentary vertical view of the jack on an enlarged scale.

Fig. 3 is a view similar to Fig. 2 showing the operating means in position to permit the jack to retract.

Fig. 4 is an enlarged view taken on line 4—4 of Fig. 1; and

Fig. 5 shows a modified form for the operating handle of the jack.

2

Referring now in detail to the drawings, a conventional hydraulic jack is indicated at 12 comprising a lifting plunger 14 operating in an inner sleeve 15 of the jack. An outer sleeve 16 defines a reservoir 17 containing a supply of fluid for operating the lifting plunger 14. Formed integral with the jack housing at the base thereof is a cylindrical housing 19 extending radially outwardly from the jack, and shown in this instance inclined slightly upwardly. The outer end 20 of the housing 19 is open for the insertion of the jack which will be described in detail later.

Inserted in the housing 19 at the inner end thereof is an insert 21 with an inner reduced threaded end 22 which threads into a cooperating bore in the base of the jack. The insert 21 is provided with packing means 24 at its outer end having its inner end of reduced outer diameter forming a circumferential passage 25 between itself and the interior of the housing, and is provided with a central bore 26 having a restriction 27 therein. A radial port 29 is formed in the wall of the insert 21 communicating between the circumferential passage 25 and bore 26.

The base of the jack is provided with a port 30 leading from the reservoir 17 to the circumferential passage 25 and is also provided with a passage 31 communicating between the inner end of the bore 26 and the interior 32 of the jack formed by the inner sleeve 15. A ball valve 34 seats on and closes the inner end of the port 29 and is normally held in place thereon by a spring 35. A pin or plunger 36 rests idly in the restriction 27 during the lifting operation of the jack. The pin 36 is of such small diameter that it does not seriously impede the passage of fluid through restriction 27. On the inner side of the restriction 27 is another ball valve 37 which seats against the restriction and is normally held in place thereon by a spring 39. The length of the pin 36 is slightly less than the distance between the ball valves 34 and 37 so that both of the ball valves may be seated against their respective ports simultaneously.

A pump rod 40 is positioned in the bore 26 and is held in place therein by a sleeve 41 threaded into the outer end of the insert 21. As the pump rod 40 is reciprocated in the bore 26, the fluid system is actuated to extend the jack. On the back stroke of the pump rod 40 the fluid flows from the reservoir 17 through the passage 30, the circumferential passage 25 and the radial port 29 into the interior of the bore 26,

In this operation the ball valve 34 is unseated. On the forward stroke of the pump rod 40 the fluid thus trapped in the bore 26 is forced through the restriction 27 unseating the ball valve 37 which permits the fluid to pass through the passage 31 into the interior of the jack, operating the lifting plunger 14.

A port 42 is formed near the upper end of the sleeve 15 communicating between the interior of the sleeve 15 and the reservoir 17, completing the circulating passage for the fluid system. When the lifting plunger 14 is raised to its uppermost limit the packing 44 thereon rises above the port opening 42 permitting free circulation of the fluid in the jack and relieves the lifting plunger 14 of any further operating action.

To effect lowering of the lifting plunger, the pump rod 40 is extended farther into the bore 26 than was done in the lifting operation. Reference may be had to Fig. 3. The result of this action is that the inner end of the pump rod 40 forces the ball valve 34 off of its seat on the radial port 29 and at the same time forces the pin 36 in the same direction which in turn unseats the ball valve 37 with respect to its port. When the pump rod 40 is thus held in this position, the lifting plunger 14 is lowered as the passage of the fluid will be from the interior of the sleeve 15 through the bore of the jack to the reservoir 17, or the reverse of the process as described in connection with the lifting operation.

Referring to Fig. 1, the jack handle proper is indicated generally at 45. The main length of the handle consists of a tubular housing 46 and a slightly enlarged section of tubular housing 47 fitted over the inner end of the housing 46 and welded thereto as indicated at 49. The housing section 47 extends into the interior of the housing 19 of the jack and is held in place therein by a quick release spring detent device 50 which can be observed in Fig. 4. A spring clip 51 is secured to the housing 19 by a rivet 52 and carries a pin 54 riveted therein and extending through registered openings formed in the housing 19 and 47. The extended end 55 of the clip can be manipulated for flexing the clip for quickly attaching and detaching the pump handle.

An actuating rod 56 is slidably positioned in the interior of the housing 46 and is provided with collars 57 for aligning it within the housing. A lug 59 is struck up inwardly from the housing 46 to cooperate with the collar 57 and thereby prevent the actuating rod 56 from sliding out of the handle housing. The inner end of the actuating rod engages a collar 60 formed on the outer end of the pump rod 40. A compression spring 61 surrounds pump rod 40 and sleeve 41 and is secured between collar 60 and the packing washer 23, biasing the pump rod 40 outwardly. The spring 61 loses its compression just beyond the point of the outward stroke of the pump rod 40 in the pumping operation, making it unnecessary to have positive engaging means for preventing the pump rod 40 from falling out of place when the handle is detached. The pump rod 40 has a tight fitting engagement with sleeve 41.

Secured to the outer end of the housing 46 forming the main length of the handle is a hand grip 62 comprising a tubular portion 64 fitting over the housing 46 and a generally perpendicularly extending portion 65. The hand grip may be riveted to the housing 46 as shown at 66. The portion 65 of the hand grip is U-shaped in formation with its open end extending forwardly as

indicated at 67. A lever 69 is pivotally secured at 70 in the side walls forming the hand grip 65 near the upper end or near the main shaft of the handle. The upper shorter end 71 of the lever extends up into the interior of the housing 46 and has a rounded forward edge 72 freely engaging the rear surface of the collar 57 on the outer end of the actuating rod 56. The lower end 74 of the lever 69 extends downwardly and is approximately the same length as the hand grip. The lever 69 may be actuated by gripping both this lever and the hand grip in the hand and compressing the lever into engagement with the hand grip. By this action the actuating rod is forced forward and thereby the pump rod is also forced forward, actuating the fluid system in the jack.

A U-shaped clip 75 is pivotally secured at 76 to the lower end of the hand grip. The clip 75 when in the position shown in Fig. 1 limits the compressing movement of the lever 69 at that point in the lifting operation of the jack. To actuate the jack for lowering the lifting plunger, the clip 75 is swung back from the full line position to the dotted line position shown in Fig. 1, enabling the lever 69 to be compressed farther into the hand grip 62 where it finally contacts set screw 77 which is the ultimate limit to which it can be compressed. The set screw 77 is mounted in a boss 79 formed in the hand grip and it may be adjusted through an opening formed in the back side of the hand grip. When the lever 69 is compressed until it contacts the set screw 77, the actuating rod 56 and pump rod 40 are forced forward into the jack sufficiently far to unseat the ball valves 34 and 37 permitting the lifting plunger to lower. The position of the pump rod for this operation is shown in Fig. 3. The extent to which these ball valves are removed from their seats determines the speed at which the lifting plunger lowers, and this may be controlled by adjusting the set screw 77.

The lower end 74 of the lever 69 is provided with a notch 80 into which the clip 79 may be inserted for securing the lever in locked position when the handle is detached from the jack.

Fig. 5 shows a modification of the hand grip for the handle. In this figure the hand grip 81 consists of a portion 81 which is substantially a linear extension of the handle as a whole. The lever 82 is correspondingly shaped to conform to the hand grip, but its mechanical advantage need not be altered nor will it be less convenient for operation.

Although I have herein shown and described a preferred embodiment of my invention, manifestly it is susceptible of modifications and rearrangement of the parts without departing from the spirit and scope thereof. I do not, therefore, wish to be understood as limiting this invention to the precise form herein disclosed except as I may be so limited by the appended claims.

I claim as my invention:

1. In a jack of the class described, the combination of a vertical lifting plunger, a fluid system for raising the lifting plunger, a rigid handle rigidly connected to the jack and extending outwardly therefrom, a hand grasp on the outer end of said rigid handle for positioning the jack as a whole, actuating means in said handle for actuating the fluid system in the jack for raising the lifting plunger, and hand operated means on the outer end of said rigid handle for operating said actuating means, said hand operated means on being moved in one direction serving to raise the lifting plunger and on continued movement in the

same direction moving to a predetermined position for conditioning said actuating means to permit the lifting plunger to be lowered.

2. In a jack of the class described, the combination of a vertical lifting plunger, a fluid system for raising the lifting plunger, a rigid handle rigidly connected to the jack and extending outwardly therefrom, a hand grip on the outer end of said rigid handle for positioning the jack as a whole, actuating means in said handle for actuating the fluid system in the jack, hand operated means on the outer end of said rigid handle coacting with said hand grip for operating said actuating means, said hand operated means on being moved in one direction serving to raise the lifting plunger and on continued movement in the same direction moving to a position whereby the lifting plunger lowers, and means on said hand grip for limiting the movement of said hand operated means.

3. The combination with a jack, comprising a vertical lifting plunger, a fluid system for raising the lifting plunger, a rigid handle rigidly connected to the jack and extending outwardly therefrom, a hand grip on the outer end of said rigid handle for positioning the jack, a rod in said handle slideable longitudinally therein and extending into the body of the jack to the fluid system therein for actuating the fluid system, said rod on inward motion thereof serving to raise the lifting plunger, spring means in said handle biasing said rod outwardly, and a lever mounted on said hand grip, one end of said lever loosely engaging the outer end of said rod, the other end of said lever coacting with said hand grip and on being moved toward the same serving to force said rod inwardly.

4. In a jack, the combination of a lifting plunger, a fluid system for operating the lifting plunger, a tubular housing rigidly connected to the jack and extending outwardly therefrom, a pump rod slideable longitudinally in said tubular housing and extending into the fluid system for actuating the same, spring means in said tubular housing biasing said pump rod outwardly short of displacing said pump rod from said housing, a handle insertable around said spring means in said tubular housing and forming a rigid coaxial extension thereof, means for detachably securing said handle in said tubular housing, an actuating rod in said handle loosely engageable with the outer end of said pump rod and forming a coaxial extension thereof, a hand grip on the outer end of said handle for positioning the jack as a whole, and means coacting with said hand grip for operating said actuating rod and thereby said pump rod.

5. In a hydraulic jack, the combination of a lifting plunger, a fluid system for operating the lifting plunger, a tubular housing rigidly connected to the jack and extending outwardly therefrom, a pump rod slideable longitudinally in said tubular housing and extending into the fluid system for actuating the same, said pump rod operating to extend the lifting plunger on being forced inwardly in said tubular housing, spring means biasing said pump rod outwardly, a handle insertable in said tubular housing and forming a rigid coaxial extension thereof, quick-release spring means for detachably receiving said handle in said tubular housing, a hand grip on the outer end of said handle for positioning the jack as a whole, an actuating rod in said handle loosely engaging the outer end of said pump rod, and a lever mounted on said hand grip loosely engag-

ing the outer end of said actuating rod, said lever, acting through said actuating rod, forcing said pump rod inwardly on being operated against said hand grip.

5 6. In a hydraulic jack, the combination of a lifting plunger, a fluid system for operating the lifting plunger, an open-ended housing rigidly connected to the jack and extending outwardly therefrom, pump means in said housing for actuating the fluid system spring means in said housing biasing said pump means outwardly short of displacing said pump means from said housing, a handle insertable around said spring means in the open end of said housing and forming a rigid coaxial extension thereof, means for detachably securing said handle in said housing, an actuating rod slideable in said handle and loosely engaging said pump means, means on said actuating rod for centering the same within said handle, means 10 limiting the forward movement of said actuating rod and for retaining the actuating rod in said handle, a hand grip on the outer end of said handle for positioning the jack as a whole, and a lever mounted on said hand grip and loosely 15 engaging the outer end of said actuating rod, said lever on being operated against said hand grip acting through said actuating rod to operate said pump means.

20 7. In a jack of the class described, the combination of a lifting plunger, a fluid system for operating the lifting plunger, an open-ended housing rigidly connected to the jack and extending outwardly therefrom, pump means in said housing for actuating the fluid system, a handle insertable in the open end of said housing forming a rigid coaxial extension thereof, means for detachably securing said handle in said housing, an actuating rod in said handle engageable with said pump means, said actuating 25 rod on being forced inwardly operating said pump means to extend the lifting plunger and on continued movement in the same direction moving said pump means to a position whereby the lifting plunger retracts, a hand grip on the outer end of said handle, a lever mounted on said hand grip and engageable with the outer end of said actuating rod, said lever on being compressed against said hand grip forcing said actuating rod forward, and a swingable clip on said hand grip limiting the compressing movement of said lever.

30 8. In a jack of the class described, the combination of a lifting plunger, a fluid system for operating the lifting plunger, an open-ended housing rigidly connected to the jack and extending outwardly therefrom, pump means in said housing for actuating the fluid system, a handle insertable in the open end of said housing forming a rigid coaxial extension thereof, means for detachably securing said handle in said housing, 35 an actuating rod in said handle engageable with said pump means, said actuating rod on being forced inwardly operating said pump means to extend the lifting plunger and on continued movement in the same direction moving said pump means to a position whereby the lifting plunger retracts, a hand grip on the outer end of said actuating rod, said lever on being compressed against said hand grip forcing said actuating rod forward, a swingable clip on said hand grip limiting the compression movement of said lever, and stop means limiting the final compression movement of said lever beyond the point of said swingable clip.

70 9. In a hydraulic jack, the combination of a

lifting plunger, a fluid system for operating the lifting plunger, an open-ended housing rigidly connected to the jack and extending outwardly therefrom, pump means in said housing for actuating the fluid system, a handle insertable in the open end of said housing forming a rigid coaxial extension thereof, means for detachably securing said handle in said housing, an actuating rod in said handle engageable with said pump means, said actuating rod on being forced inwardly operating said pump means to extend the lifting plunger and on continued movement in the same direction moving said pump means to a position whereby the lifting plunger retracts, a hand grip on the outer end of said handle, a lever mounted on said hand grip and engageable with the outer end of said actuating rod, said lever on being compressed against said hand grip forcing said actuating rod forward, a swingable clip on said hand grip limiting the compression movement of said lever, stop means limiting the final compression movement of said lever beyond the point of said swingable clip, and means on said lever coacting with said swingable clip for restricting the movement of said lever in either direction.

10. In a jack structure, the combination of a jack element and a handle element therefor, said jack element including mechanism operative to extend the jack element for lifting purposes, said handle element being inherently rigid, and means for detachably connecting said handle element to said jack element, said handle element including on its outer end operating mechanism for said jack element extending mechanism and an operative connection between said operating mechanism and said extending mechanism, said operative connection extending through said rigid handle and being adaptable for movement to one position for effecting lowering of the jack element extending mechanism, and blocking means to prevent movement of said operating mechanism to said one position during raising movements of the jack.

11. In a jack structure, the combination of a jack element and a handle element therefor, said jack element including mechanism operative to extend the jack element for lifting purposes, said

5 handle element being inherently rigid, and means for detachably connecting said handle element to said jack element, said handle element including on its outer end operating mechanism for said jack element extending mechanism and an operative connection between said operating mechanism and said extending mechanism, said operative connection extending through said rigid handle and being adaptable for movement to one position for effecting lowering of the jack element extending mechanism, and blocking means to prevent movement of said operating mechanism to said one position during raising movements of the jack, said blocking mechanism constituting a latch for said operating mechanism when the jack is not in use.

12. In a handle for a jack of the class described, the combination of a main body, an actuating rod slideable in said body, a hand grip on one end of said handle, said hand grip being U-shaped in cross section with its open edge away from the hand when being used, a lever mounted on said hand grip having one end extending into the interior of said main body and loosely engageable with said actuating rod, and the other end operable to compressed position in said hand grip and to extended position, swingable clip means on the outer end of said hand grip for limiting the compression movement of said lever, adjustable stop means within said hand grip for defining the limit of compression movement of said lever, and detent means on the outer end of said lever engageable with said swingable clip for restricting the movement of said lever in either direction.
